UNITED STATES PATENT OFFICE

EDWARD O. TINSLEY, OF NEW YORK, N. Y., ASSIGNOR TO ROBERT GAIR COMPANY, OF NEW YORK, N. Y., A CORPORATION OF NEW YORK

COLLAPSIBLE CARRYING CONTAINER

Application filed December 22, 1928. Serial No. 327,805.

The present invention relates to containers, and has particular reference to a portable, display carton assembled from a single blank.

Among the many advantages that may be cited in favor of a carton assembled from a single blank, two are particularly important. One of these involves the economy attendant upon the ready manufacture of the blanks in quantity, the other, the fact that the carton blanks may be shipped in flat, collapsed packages to the distributor.

Other desirable advantages are to be noted. The material such as pasteboard, strawboard and the like, out of which the carton is fabricated, may be fed through the proper machine in webbed form. Again, the blanks may be cut and scored from the webs with a minimum of waste, and labor expense. Lastly, the finished blanks may be assembled in collapsed or knocked-down condition for ready use by the consumer.

Thus, one of the important objects of the present invention is to provide a carton which may be speedily and easily assembled from a single blank, and when in assembled or erected condition, be capable of receiving articles, such as bottles containing beverages, and lastly, be so constructed as to be readily adapted for safe carriage, and prominent display of the articles contained in the carton.

Another object of the invention is to provide handle means on a carton, the former being integral with the carton blank, whereby the carton may be carried with facility when filled with articles, such as bottles.

Another object of the invention is to provide a portable, display carton so designed that the load, carried thereby, may be properly balanced and distributed, whereby a thinner grade of board stock may be utilized in the fabrication of the carton.

And another object of the invention is to provide a portable carton, made from a single blank, so constructed and designed, that the portions of the carton subjected to loads, strains and stresses, are reinforced with a plurality of duplicate walls.

Still another object of the invention is to provide a portable carton of a display type with means, whereby a plurality of articles, such as beverage bottles, may be carried therein, portions of the carton being constructed to act as separators between the bottles to prevent their intimate contact, and to act as buffers to obviate rattling and breaking of the bottles.

And still another object of this invention is to provide a display carton, fabricated from a one-piece blank, whereby a single printing operation will provide one plain surface of the blank with all the desired printing matter, and which carton when the blank is erected in operative position, will have all of its printed sides exposed, thus enhancing the advertising value of the carton, and prominently displaying the contents thereof.

And other objects of the invention are to improve generally the simplicity and efficiency of portable cartons, and to provide a device of this kind which is economical, durable and reliable in operation, and economical to manufacture.

A further object is to provide a container, blanked out of one piece, wherein the contents may be carried, either completely enclosed by suitable closing flaps, or carried and displayed by folding the closing flaps in open, content display position, as will later be disclosed, and at the same time be collapsible into a flat folded assembly to be shipped in bundles for ready erection when required for use.

Many of the features of the invention may be used without employing all of them, as some of those which are not essential may be omitted without departing from the spirit of the invention, though such omission may to a greater or less extent affect the quality of the product. Moreover, the device is capable of receiving various mechanical expressions without departing from the spirit of the invention itself; and, for the purpose of describing the invention, there is illustrated in the accompanying drawings, the preferred forms of apparatus.

In these drawings:

100

Fig. 1 is a perspective view of the carton in erected condition and ready for the introduction of articles therein.

Fig. 2 is a vertical sectional view, taken through the middle of Fig. 1, and showing in dotted lines a plurality of bottles in position therein.

Fig. 3 is a partially erected view of the blank showing the first step in folding it into erected position as shown in Figs. 1 and 2.

Fig. 4 is a developed view of the carton blank, scored, and in position for the first motion of erection, this view being the reverse of that shown in Fig. 3.

Fig. 5 is a view of the carton in collapsed position and ready to be moved into the position shown in Fig. 1.

Fig. 6 is a sectional view taken on the line A—B, Fig. 3, this section being similar for the opposite carton forming member.

Fig. 7 is a perspective view of a modified form of carton.

Fig. 8 is a vertical sectional view taken through the middle of Fig. 7.

Fig. 9 shows a developed view of the blank used to form the carton shown in Fig. 7.

Fig. 10 is a perspective view of a container, modified over that shown in the preceding figures, wherein there is provided additional means for completely enclosing the container, leaving it rectangular in contour.

Fig. 11 shows a similar view with the handles extended.

Fig. 12 shows a similar view with the enclosing means folded back, displaying the container interior.

Fig. 13 shows the device in flat collapsed shipping condition.

Fig. 14 is a blank layout, similar to Fig. 4, showing how the enclosing means is developed from a single flat sheet in conjunction with the container forming elements.

Referring to Figs. 1 to 6 inclusive, and as illustrated in the perspective view, Fig. 1, the device comprises substantially an outer four-walled casing 1, which surrounds and encloses a pair of opposed open side compartment forming members 2.

These members 2 are located, back to back, within the surrounding casing 1, each of the carton forming members 2 and the casing member 1 being formed from a single blank, as will be later described.

The adjacent ends of the casing member 1 are secured, as at 3, Fig. 1 so as to form an outer embracing casing member as shown. The side walls 4 of the members 2, where they adjoin the back forming flap 5, are tapered for a portion of their length. Thus, there is provided an open and accessible entrance for the articles to be placed therein, and also form at their lower casing embraced portions, as stabilizers for maintaining the casing member 1 in rectangular open position, when

erected from the collapsed position, shown in Fig. 5.

The back flap forming members 5, 5 are each provided with a semi-blanked out slot member 6 near the top thereof whereby to form a hand-grip opening, the flap 7 blanked therefrom, being preferably hinged to one side of said slotted opening whereby to reinforce the hand hole 6 against tearing when the carton is being carried.

The back members 5 are, further, each provided with a pair of blanked-out, undetached, hinged rectangular portions 8, 8. These latter portions are blanked out of the said back members, being slit out and hingedly scored thereto, to form outstanding buffer members, whereby the carton may be easily used for carrying bottles. As shown in Fig. 2, these flaps 8 may be extended outwardly to form buffers between the adjacent bottles, to prevent contact thereof, thus eliminating rattling noise and obviating accidental breakage of the bottles.

When the carton is in erected form, as shown in Figs. 1 and 2, it provides rigid, substantially rectangular carrying members. The bottle load is suspended upon, and carried by the middle load-carrying section, which is formed by the two back members 5, which are so developed in the folding of this carton as to run intermediately of the carton as shown in Fig. 2.

Thus, as in the case of the bottles, each bottle carried is isolated, one from the other, and out of contact with each other, thereby supporting each bottle in a buffer-isolated, carrying position.

In Fig. 4, which is a developed view of the carton, the component parts of Fig. 1 are shown in stretched out or blank form, and the particular parts of the blank will be described in detail. The casing member 1 is formed by a longitudinal strip, and comprises a tab portion 9, used as a securing means, and is separated from the rest of the strip 1 by a score line 9'. The carton side element 10, Fig. 2, is formed by the panel 10, Fig. 4, and is scored away from the blank by lines 10' and 10''. A second panel 11 is scored away from 10 by scoring lines 10'' and 11'. A third panel 12 is scored away from panel 11 and is also scored at 12'. A fourth panel 13 forming a second carton side element 13, Fig. 2, is scored away from panel 12 by scoring line 12'. Panel 13 is, further, scored from the main carton forming member by a second score line 13''. A fifth panel 14 is scored away from panel 13 by the score line 13'. A sixth panel 15 is scored away from panel 14 by score lines 14', the outer edge of this latter panel 15 terminating at the end of the casing strip, opposite tab 9.

The casing strip 1 is, thus, divided into a series of panels and flaps scored relative one to the other, and scored away from the main

carton forming portions by the score lines 10' and 13''. The relative positions of these score lines and the panels are indicated in Fig. 1, forming their casing forming positions when erected.

The two back to back elements 5 carry similar numerals, as described for Fig. 1, and are readily identified in Fig. 4. To further understand the component forms, it will be noted that there are between each of the members 5, 5, Fig. 4, and the casing strip 1, a connecting panel 16. These panels 16 are scored away from the casing panels 13 and 10 by the score lines 13'' and 10', and for the members 5, 5 by score lines 16', 16'', and these two panels 16 are bendable away from the casing strip 1, as will be later described. These two panel members 16, when the back to back members 5, 5 are assembled, form the inside bottom of the carrying compartment, as shown in Fig. 2.

The back members 5 are provided with opposing side members 4, in the nature of wing panels, which are connected to the back forming members 5 by score lines 4'. The back members 5 with their hinged bottle buffer members 8 scored as at 8' are also shown in the blank layout in Fig. 4. The handle slotted member 6 is also shown, with the hinged member 7.

With the blank in the position shown in Fig. 4, in order to erect the carton into non-operative, collapsed shipment position ready to be quickly opened, the following operations are to be followed, it being understood that the blank as shown in Fig. 4 is with the printed surface down and the unprinted surface up toward the observer.

The first move is to bend the flaps 4 inwardly and over upon the score lines 4' so that they lie flat upon the back members 5. The members 5 with the pre-folded flap members 4 are folded upwardly on the score lines 13'' and 10', thus bringing the members 5, 5 into the position shown in Fig. 3.

Then, the entire blank is folded upon the score line 11', Fig. 3, bringing the two members 5, 5 into registration with one another. The panel member 15 is next folded over on line 14' until it registers and contacts with tab 9, and these two members are secured together by adhesive, staples, or otherwise. The blank is now in knocked-down, flat, collapsed form for shipment to the user, as shown in Fig. 5.

When the consumer receives the blank shown in Fig. 5, to erect the carton for carrying purposes, it is merely necessary to set the container up on its edge 16' and open the side flaps 4 which in turn extend the casing member 1, automatically forcing the bottom forming members 16 downwardly, bringing the hand hole slots 6 into registration with one another. Thereafter, bending the cushion flaps 8 outwardly into the associated com-

partments formed in the preceding step, the carton is ready for the reception of its load which, in the case of bottles, as previously described, permits said bottles to be carried in separate non-contacting position.

In practice, this carton is designed to carry three bottles in each back to back compartment, cushioned from one another thereby carrying a load of six beverage bottles, as desired.

One added advantage of the construction herein is that the bottles may be taken from either side, leaving one side completely empty and the carton still will function perfectly, and without distortion or accident. The entire load is supported in the carton by the two back to back members 5, 5 and the bottom forming members 16, 16, and retained against these members by the casing strip 1.

In the modification shown in Figs. 7, 8 and 9, the general structure of the carton is identical to that shown in Figs. 1-6 inclusive, and, therefore, like members will be similarly numbered. In this modification there is provided a single piece, two-compartmented carrying member, in which the casing strip 1 has extended from its upper edge a series of added panels 17, 17. These latter panels, when folded, cause the outer panels 10 and 13 to become reinforced since a double wall is formed. Accessory flaps 18, scored from panels 17 by lines 18', further increase the strength of the casing strip 1, by giving the ends of the carton a triple wall protection. When the panels 17 are folded on score lines 17', the flaps 18 cooperate with the compartment-forming walls 4, and the outer end wall panels 11, 12, 14 and 15, to provide the ends of the carton with the triple wall protection.

The carton blank shown in Fig. 9, is folded into operative shape in the same manner, as noted above for the carton shown in Figs. 1 to 6 inclusive. The score lines 11' and 14' form the collapsing scores whereby the entire carton may be collapsed and so shipped for opening. The collapsed, shipping position of this form of carton is the same as shown in Fig. 5. The casing strip 1, as explained before, retains within it, the complete assembly, ready for erection.

Here, again, the edge of panel 15 may be glued or stapled to flap 9.

It will thus be seen that I have provided a portable container which is made from a single blank, and is further capable of being folded into such a collapsed, shipping position that the user of the carton may easily and quickly move the carton members into erect, operative shape. The carton itself has been so constructed as to lend itself, with great facility, to receiving in non-contacting position articles for portage thereof from place to place, thereby obviating the danger of breakage in the case of articles, as glass bottles, due to rattling. At the same time

the erected carton has been so designed as to constantly and prominently display the said articles whether or not the carton is being carried.

5 The modifications shown in Figs. 10 to 14 inclusive are, in the main, similar to the structure described for Figs. 1 to 9 inclusive, and in these Figs. 10 to 14 like indices are utilized throughout to indicate the same parts and their functions as described for Figs. 1 to 9.

10 The modified structure in Figs. 10 to 14 has, however, additional coacting elements whereby the container described and shown in Figs. 1 to 9 is so constructed as to permit 15 the carrying container to be set up into a completely enclosed package, as in Fig. 10, with no protusions whatever, thereby to permit a plurality of such containers, when filled, to be packed in a separate outer shipping box of 20 any nature. When so shipped, and the box is opened, the separate containers may then have their handles folded outwardly as at 7, Fig. 11, whereby the containers still closed in rectangular form may be carried by hand 25 without exposure of contents.

30 A container as herein outlined forms a single hand carried container, and an excellent bottle separating and cushioning means for a shipping box, when a plurality of these containers are filled and packed into such suitable shipping box, not shown.

35 Further, as shown in Fig. 12, if such containers, when removed from the shipping box, are desired for display purposes by the vendor, or, the enclosing elements forming the outer cover for the container may be folded back and under the container and there held by the weight of the contents in display position, but ready for instant closure for a carry- 40 away sale.

45 To this end, the following disclosure will recite only such additional elements as are required to the device shown in Figs. 1 to 9, without redescription of prior parts.

50 In Fig. 14 which outlines the modification in its blank contour, the carton sides 10 and 13 have scored from their lower edges at *a* and *b* respectively panels *c*—*c* of the same width as the said sides. These in turn have scored at *d'* therefrom depending narrow panels *d*—*d* and, scored at *4'* from these latter panels, are a pair of tuck-in flaps *e*—*e*.

55 Further, the four side walls 4, which function as described for Fig. 1, are each provided with an extended bending flap *f*, which are each scored from walls 4 by a score line *g*. The flaps *f* are cut clear at the lines *h*, to permit of right angled folding from the handle forming elements 7—7.

60 The container thus described, is similar to that shown in Fig. 1, except for the last described elements, alphabetically indexed, and which are added to create a cover or container enclosing means, as set forth. In order to 65 permit the folding of the handle flap *h*, with-

in the container dimensions, as in Fig. 10, the handle flaps *h* are scored from panel 5 by scored lines 5'—5' whereby they may be folded downwardly along the upper ends of side panels 4—4, and thus be out of the way for 70 shipping box packing.

When removed from the shipping box the handle flaps may be erected as in Fig. 11, and the handle flaps arranged as previously described. In folding the handle flaps *h* down, 75 Fig. 12 illustrates the position for either closing or opening the same. In this figure the end flaps *f* are first folded down to form supports for the handle flaps and to reinforce the upper corners of the side members 4—4. 80

In Fig. 12, the enclosing flaps *c*—*c* are shown folded downwardly with the flaps *d*—*d* and *e*—*e* folded under the bottom of the container. In Figs. 10 and 11 the enclosing flaps are shown folded up over the upper ends 85 and tucked by flaps *d*—*e* between backs 5 to lock the assembly in closed position with handles *h* in or out as required.

The container may be collapsed flat for bulk shipping as indicated in Fig. 13, in 90 which the various panels and scores in this flat view are, it is thought, sufficiently identified.

The foregoing detailed description has been given for clearness of understanding. Hence, 95 any unnecessary limitation should be understood. The appended claims should be construed as broadly as permissible in view of the prior art.

What I desire to claim is:

1. In a portable carton, formed from a single blank, and adapted to receive bottles in display position, a pair of vertical members adapted to be positioned back to back, a pair of tapered flaps flexibly connected to 100 each of said members, adjacent flaps of each member lying in the same plane and forming the end walls of said carton, a pair of panels flexibly connected to said vertical members, said panels forming the bottom of said carton and lying in the same plane, said bottom panels being in contact with said flaps when in carton-forming position, an elongated strip, including reinforcing panels and flaps, 105 flexibly connected to said bottom panels, said reinforcing panels and flaps being positioned between said strip and bottom panels and 110 flexibly connected thereto, said strip comprising side panels and end panels flexibly connected to one another, one of said end panels being provided with a weakened portion and being positioned between said side panels, the other end panel also having a weakened portion and being positioned between side 115 panels only when secured to one of said side panels, said strip, in carton-forming position, embracing said end flaps and back members, 120 said reinforcing panels being in face to face contact with said strip side panels, and said reinforcing flaps being positioned between 125 130

5 said strip end panels and said end flaps, when said strip is in said embracing position, said strip cooperating with said end flaps, back members, and bottom panels to form a pair of adjacent compartments having open tops, each of said back members being further provided with a pair of flaps flexibly connected thereto, said flaps acting as separating flaps between articles placed in each compartment
 10 to prevent contact of said articles, said back members being further provided with registering slots to receive fingers whereby said carton may be carried when loaded with said articles, said strip contacting with said end flaps for only a portion of the length of said flaps thereby affording prominent display to articles positioned in said compartments, said carton being adapted to be collapsed into shipping position by placing said end flaps
 20 and bottom panels into face to face contact with said back members and bending said strip along the weakened portions of said strip end panels.
 2. In a carton, formed from a single blank, 25 and adapted to receive bottles in display position, a pair of members adapted to be positioned in back to back relation, a pair of flaps connected to each of said members, adjacent flaps of each member forming the end walls
 30 of said carton, a pair of panels connected to said vertical members, said panels forming the bottom of said carton, said bottom panels being in contact with said flaps when in carton-forming position, an elongated strip, including reinforcing members, connected to said bottom panels, said strip comprising side panels and end panels connected to one another, said end panels being provided with weakened portions, said strip in carton-forming position embracing said end flaps and back members, certain of said reinforcing members being in face to face contact with said strip side panels, and others being positioned between said strip end panels and
 45 said end flaps, when said strip is in said embracing position, said strip cooperating with said end flaps, back members, and bottom panels to form a pair of adjacent compartments having open tops, the side and end walls of which compartments are reinforced, each of said back members being further provided with separating flaps between articles placed in each compartment to prevent contact of said articles, said strip contacting
 50 with said end flaps for only a portion of the length of said flaps thereby affording prominent display to articles positioned in said compartments, said carton being adapted to be collapsed in to shipping position by bending said strip along the weakened portions of said strip end panels.
 3. In a container, comprising two separate substantially double walled compartments, the outer wall portion of one of said compartments being continuous with the outer wall

portion of the other of said compartments, a joining member on each of said compartments, secured to the end walls thereof, for locking the said compartments into back to back relation, and suspension means on each 70 of said members, whereby said container may be carried.

4. In a container, comprising a pair of separate compartments, a one piece blank of cardboard or the like, including a pair of panels, to be placed into back to back relation, to form a two ply joining member for said compartments, side flaps on said panels, disposed transversely thereto, when said container is erected, and a strip, integral with 75 said panels, disposed to encompass said compartments, to form side walls and end walls therefor, said end walls to be secured to said side flaps, whereby to bring said panels into back to back relation and to retain the same in 80 said relation.

5. The elements of claim 3, said joining members being integral with the bottoms of said compartments and said suspension means comprising registering slots on said joining 90 members for the hand of a person to pass therethrough.

6. The elements of claim 4, combined with added panels on said blank, positioned between said first mentioned panels and said strip and foldable therewith on horizontal score lines, said added panels having each thereon integrally therewith a pair of accessory flaps, said added panels to reinforce the side walls of said compartments and said accessory flaps to reinforce the end walls thereof when said container is erected. 100

7. In a container, comprising a pair of separate compartments, a one piece blank comprising partition panels, for a pair of joining members, to lock the said compartments into back to back relation, whereby the container may be maintained in display position, and a girth strip comprising side wall panels and end wall panels, foldably connected to each other on vertical score lines, when said container is erected, said end wall panels being provided each at the middle thereof with a collapsing score line, which is vertically disposed when said container is erected. 105

8. The elements of claim 4, combined with added panels on said blank, positioned between said first mentioned panels and said strip and foldable therewith on horizontal score lines, said added panels to reinforce the side walls of said compartments when said container is erected. 110

9. A container comprising two separate compartments, a wall portion of one compartment being flexibly connected to a wall portion of the other, and strip means for locking the compartments into back to back relation, and means provided in each compartment whereby said container may be carried, said means comprising registering slots to 115
 120
 125
 130

ceive fingers whereby said carton may be carried when loaded with said articles, said strip contacting with said compartments for only a portion of the length of said flaps thereby affording prominent display to articles positioned in said compartments.

Signed at New York, in the county of New York and State of New York, this 21st day of December, A. D. 1928.

EDWARD O. TINSLEY.
